(57) **CLAIM**

The ornamental design for a charging stand for vacuum cleaner, as shown and described.

DESCRIPTION

FIG. 1 is a front, top and right-side perspective view of a charging stand for vacuum cleaner showing my new design;
FIG. 2 is a front view thereof;
FIG. 3 is a rear view thereof;
FIG. 4 is a top view thereof;
FIG. 5 is a bottom view thereof;
FIG. 6 is a right-side view thereof;
FIG. 7 is a left-side view thereof; and,
FIG. 8 is a perspective view shown in a state of use.
The dash-dash broken lines shown represent portions and the environment of the charging stand for vacuum cleaner and form no part of the claimed design. The dash-dot broken lines shown in FIG. 5 represent the bounds of the claimed design that form no part of the claimed design.

1 Claim, 8 Drawing Sheets
